TOY JUMPING STANDARD

Renee Piper, 3857 Cleveland, Skokie, Ill.

Filed Feb. 20, 1961, Ser. No. 63,998

Term of patent 7 years

(Cl. D34—5)

FIGURE 1 is a perspective view of a toy jumping standard showing my new design, with the additional standard and bar shown in broken lines for illustrative purposes only; and

The ornamental design for a toy jumping standard, substantially as shown and described.
